GREENHOUSE SASH

Philip L. McKee, Pana, Ill.

Application September 30, 1931
Serial No. 566,028

5 Claims. (Cl. 108—16)

This invention relates to greenhouse construction generally and particularly to sash construction for greenhouses, and the primary object of the invention is to provide a new and improved 5 ventilator sash which is rigid in construction, which is efficient in operation, and which may be readily and economically manufactured and assembled.

Other attendant objects of the invention are 10 the provision of a novel greenhouse ventilating sash which is hingedly connected to the greenhouse ridge bar in such a manner that the ridge bar cap provides a covering at the upper end of the sash thereby preventing rain and snow 15 from getting under the sash at its upper hinged end; the provision of a sash which will not warp and twist due to exposure to the elements, which 20 is tight fitting and reinforced to make the sash easily operable by mechanical sash operating devices, which is provided with drip grooves in 25 the longitudinal rails to catch condensation from the underside of the glass panels, and which is made up of smaller but stronger parts than conventional greenhouse sashes and therefore dispenses with shadows.

Numerous other objects and advantages will 30 be apparent throughout the progress of the following specification.

The accompanying drawing illustrates a selected embodiment of the invention and the views therein are as follows:

Fig. 1 is a detail sectional view of a greenhouse having the improved sash and ridge bar cap.

Fig. 2 is a detail sectional view of the sash showing its construction and the manner in which it is connected to the ridge bar.

Fig. 3 is a detail transverse sectional view on the line 3—3 of Fig. 2.

The greenhouse to which the sash is applied is preferably of the type disclosed and claimed in applicant's copending application, Serial No. 542,756, filed June 8, 1931. The greenhouse comprises a longitudinal ridge bar 5 to which a metal ridge cap 6 is attached. The cap 6 has a relatively flat upper side 7 from which side legs 8, 8 are bent downwardly at a predetermined angle. Rafters 9 have their upper ends connected to the ridge bar 5 and support the glass roof panels 10.

The improved ventilating sash, which is designated generally by the numeral 11, comprises a longitudinal angle iron upper rail 12, Fig. 2, which has legs 13 and 14, the leg 13 extending 55 across the top or upper faces of the longitudinal

sash bars 15 while the angle leg 14 engages the upper ends of the sash bars 15.

The sash bars 15 are preferably made of wood and have outwardly extending shoulders 16, 16 which support glass sash panels 17. Grooves 18 are provided in the bars 15 for the purpose of catching any water which may accumulate on the underside of the sash and drain this water to the outside of the greenhouse preventing it from dripping inside.

The sash 11 is positioned relative to the ridge bar so that its upper end will extend beyond a leg 8, which leg provides a cover at the upper end of the sash preventing rain and snow from getting in the space between the sash and the 70 greenhouse roof and falling inside of the greenhouse.

A hinge 19, having a relatively long leaf 20 and a relatively short leaf 21, pivoted together at 22, is provided for hingedly or swingingly attaching the sash to the greenhouse. The long leaf 20 of the hinge is fastened to the sash in any convenient manner, such as by screws 23, while the short leaf 21 is fastened to a leg 8 of the ridge cap by means of fasteners 24. Thus the sash is hingedly connected to the metal ridge cap thereby assuring positive operation. The over-hang of the ridge cap 6 covers the joint at the upper end of the greenhouse at the ridge bar.

The sash 11 has a lower or bottom rail 25 which is made of metal and is relatively narrow to assist in eliminating shadows. This rail 25 has an upper leg 26 upon which the glass sash panels 17 rest, and an inturned leg 27, which rests upon a metal channel-shaped cross header 28, which cross head supports the bottom of the sash. Screws 29 hold the rail 25 to the bars 15 while fastening means 30 fasten the header 28 to the rafters 9. Glass clips 30' are engaged by the glass roof panels 10, while end members 31, held by the screws 29, hold the glass sash panels 17 in place, there being zinc clips 32 positioned in the manner shown for the purpose of providing a resilient connection between the end rails 25 and the glass 17.

Weep holes 33, spaced at intervals, may be provided in the bottom rail 25 as shown for permitting water draining along the bottom of the sash as well as water carried by the drip grooves 18 to pass through the rail 25 and discharge onto the main roof.

The ends of the bars 15 may have their ends cut away as indicated at 34 so that water drained into the rail 25 may find its way to the

weep holes 33 and then through the weep holes and onto the roof.

Other holes 35 may be provided in the header 28 to permit any condensation water finding its way into this header to drain out thereof and onto the main roof.

The invention provides a sash which is rigid, which will not warp, which reduces shadows in a greenhouse and which is positive in operation.

10 The manner in which the sash is connected to the ridge cap provides for a covered connection preventing snow, ice, and water from getting in the joint. The sash can be economically manufactured and cannot be torn off in a wind storm 15 like the conventional sash.

Changes may be made in the form, construction, and arrangement of the parts without departing from the invention or sacrificing any of its advantages, and the right is hereby reserved 20 to make all such changes as fairly fall within the scope of the following claims:

The invention is hereby claimed as follows:

1. In a greenhouse, a sash therefor and comprising longitudinal sash bars, an angle iron 25 upper rail connecting said bars, an angle iron lower rail connecting said bars, and glass panels supported by said bars, said bars having drip grooves therein leading to the lower rail, said lower rail having weep holes provided therein 30 to permit water drained into the lower rail to flow therethrough, said bars having their lower ends cut away to provide a drain passage longitudinally of the lower rail.

2. In a greenhouse, a sash therefor and comprising longitudinal sash bars, an angle iron upper rail connecting said bars, an angle iron lower rail connecting said bars, and glass panels supported by said bars, said bars having drip 35 grooves therein leading to the lower rail, said lower rail having weep holes provided therein to permit water drained into the lower rail to flow therethrough, said bars having their lower ends cut away to provide a drain passage longitudinally of the lower rail, a metal header spacing 40 the bottom of said sash from the roof of the greenhouse a predetermined distance, and means for hingedly fastening the sash to a part of the greenhouse.

3. The combination with a greenhouse having a roof including rafters, panels supported by said rafters, a central ridge bar at the upper ends of the rafters, a metal ridge cap fastened to said ridge bar, and a leg on said ridge cap, of a sash comprising longitudinal sash bars having drip grooves provided therein, metal upper and lower sash rails connected to the ends of said sash bars, a hinge connected to said leg and to said upper rail, and a header spacing the lower rail from the greenhouse roof.

4. The combination with a greenhouse having a roof including rafters, panels supported by said rafters, a central ridge bar at the upper ends of the rafters, a metal ridge cap fastened to said ridge bar, and a leg on said ridge cap, of a sash comprising longitudinal sash bars having drip grooves provided therein, metal upper and lower sash rails connected to the ends of said sash bars, a hinge connected to said leg and to said upper rail, a header spacing the lower rail from the greenhouse roof, said lower rail being provided with weep holes to permit condensation carried by the grooves in the bars and by the sash to be discharged out of said lower rail and onto the 100 greenhouse roof.

5. The combination with a greenhouse having a roof including rafters, panels supported by said rafters, a central ridge bar at the upper ends of the rafters, a metal ridge cap fastened to said ridge bar, and a leg on said ridge cap, of a sash comprising longitudinal sash bars having drip grooves provided therein, metal upper and lower sash rails connected to the ends of said sash bars, a hinge connected to said leg and to said upper rail, a header spacing the lower rail from the greenhouse roof, said lower rail being provided with weep holes to permit condensation carried by the grooves in the bars and by the sash to be discharged out of said lower rail and onto the 105 greenhouse roof.
